(57) **CLAIM**

The ornamental design for a vacuum cleaner floor tool as shown and described.

DESCRIPTION

FIG. 1 is a perspective view of a first embodiment of a vacuum cleaner floor tool according to the new design.

FIG. 2 is a front view thereof.

FIG. 3 is a rear view thereof.

FIG. 4 is a left-side view thereof.

FIG. 5 is a right-side view thereof.

FIG. 6 is a top view thereof.

FIG. 7 is bottom view thereof.

FIG. 8 is a perspective view of a second embodiment of a vacuum cleaner floor tool according to the new design.

FIG. 9 is a front view thereof.

FIG. 10 is a rear view thereof.

FIG. 11 is a left-side view thereof.

FIG. 12 is a right-side view thereof.

FIG. 13 is a top view thereof; and,

FIG. 14 is bottom view thereof.

The evenly spaced broken lines in the drawings depict portions of the vacuum cleaner accessory tool and form no part of the claimed design.

The dot-dash broken line in the drawings defines the bounds of the claimed design and forms no part of thereof.

1 Claim, 14 Drawing Sheets
